UNITED STATES PATENT OFFICE.

FRANKLIN G. MATHIEU, OF CHICAGO, ILLINOIS.

TALKING-MACHINE REPRODUCER.

1,408,820.

Specification of Letters Patent. Patented Mar. 7, 1922.

Application filed March 12, 1919. Serial No. 282,156.

To all whom it may concern:

Be it known that I, FRANKLIN G. MATHIEU, a citizen of the United States, and a resident of the city of Chicago, in the county of Cook and State of Illinois, have invented certain new and useful Improvements in a Talking-Machine Reproducer; and I do hereby declare that the following is a full, clear, and exact description of the same, reference being had to the accompanying drawings, and to the numerals of reference marked thereon, which form a part of this specification.

My invention relates to talking machines and more particularly to the reproducers thereof with a view to improving the tone qualities of the machine.

Hitherto it has been usual in talking machine construction to provide a disc behind the diaphragm having a central aperture or apertures for the passage of sound from the diaphragm to the goose-neck.

The amplitude of vibration of the central portion of the diaphragm is greater than that of the parts nearer the periphery so that a greater volume of sound is obtainable from the center than from the outlying portions of the diaphragm. The tones given out by the central part of the diaphragm are, however, harsher and more strident than those from the outer portions of the diaphragm.

My invention is designed to overcome this defect.

It is an object therefore of my invention to provide means for softening the tones given out by the central portion of the diaphragm and for giving relatively greater freedom to the passage of the vibrations from the center parts of the same.

It is also an object of my invention to provide an improved form of disc for controlling the passage of the sound waves from the diaphragm to the horn or sounding box.

A further object of my invention is the provision of a sound reflector behind the center of the diaphragm adapted to reflect the vibrations received from the latter in lateral directions.

Other and further important objects of this invention will be apparent from the disclosures in the specification and drawings.

The invention (in a preferred form) is illustrated in the drawings and hereinafter more fully described.

In the drawings:

Figure 1 is a side view of a talking machine embodying my invention.

Figure 2 is a section on the line 2—2 of Figure 1.

Figure 3 is a section on the line 3—3 of Figure 2.

Figure 4 is a central section through a modified form of reproducer.

Figure 5 is a section on the line 5—5 of Figure 4.

As shown in the drawings:

1 represents the top of a talking machine provided with the usual rotating record table 2, goose-neck 3, and horn 4. As shown in Figure 2, the goose-neck is provided with a flange 5, to the periphery of which are secured a hard rubber washer 6, a disc 7 glued to the washer and an annular ring 8 by suitable means such as screws 9.

The diaphragm 10 is resiliently held in place by circular rubber tubes 11, engaging each side of the periphery of the diaphragm.

Two forms of washers and discs are illustrated. In the forms shown in Figures 2 and 3, the disc is centrally dished as at 12, so as to present a concave surface to the diaphragm so that the sound waves projected perpendicularly from the surface of the diaphragm strike the curved surface 12 and are reflected laterally outwards and towards the diaphragm from which they are again reflected obliquely and outwardly. For the passage of sound from the diaphragm to the goose-neck, a series of apertures are provided in the disc around the dished central portion 12. In the form of construction shown in Figure 2, these apertures are in the form of radial slots 13. In the washer 6, similar slots 14 are provided adapted to register with the slots 13. A central aperture 15 is formed in the washer to allow room for the rearward projection of the part 12.

The washer is glued to the metal disk 7 in order to prevent vibration of the metal disc. A rubber disc could be used in place of the combination of metal and rubber, but on account of the difficulty and additional expense of manufacturing a disc of the peculiar shape, a combination of metal and rubber is preferred. Any like material may be used in place of the rubber. It also appears that the polished metal reflector has a better sound reflecting effect than rubber or the like. An entire metallic disk thick

enough so as not to vibrate might also be used.

In Figures 4 and 5, a modified form of washer and plate are shown. In this case the disc 7^a is provided with a dished center 12^a having rectangular instead of a curved outline. This dished center is, moreover, convex on the side opposite the diaphragm instead of concave consequently there is no need of a central aperture in the washer 6.

As the part 12^a projects towards the diaphragm, an additional washer in the form of an annular ring 17, is provided between the ring 8 and the disc 7^a to hold the latter 15 out of contact with the diaphragm.

The sounds coming from the diaphragm are reflected from the curved surface 12, and some interference of the sound waves results, especially of those notes which 20 would not be concordant and therefore would produce harsh sounds. It has been determined by experiment just what distances are necessary from the diaphragm to the reflector in order to eliminate all 25 discords. Although two or more notes may be separately musical, it by no means follows that when sounded together they produce a pleasant sensation, they must be concordant. The apparatus of the invention 30 serves to eliminate these discords.

The apertures in the disc 7^a consist of a series of radially arranged holes 16. Preferably the discs 7 and 7^a are formed of metal while the washers 6 and 6^a are of 35 hard rubber but other materials may be employed as desired.

The needle 18 may be connected to the center of the diaphragm 10 in any suitable way such as that shown in Figure 1.

40 I am aware that various details of con-

struction may be carried through a wide range without departing from the principles of this invention, and I therefore do not purpose limiting the patent granted otherwise than necessitated by the prior art. 45

I claim as my invention:

1. A phonograph reproducer comprising a goose-neck flanged at one end, a washer and a disc peripherally secured to said flange and a diaphragm having a smooth 50 unbroken surface, said disc having a central dished portion concave on the side opposite the smooth face of the diaphragm and apertures therearound, said washer having a central aperture for the said dished portion 55 and other apertures adapted to register with the apertures in said disc.

2. A phonograph reproducer comprising a goose-neck flanged at one end, a washer and a disc peripherally secured to said 60 flange and a diaphragm, and said disc having a central dished portion and apertures therearound, and said washer having apertures adapted to register with said apertures in the disc. 65

3. A phonograph reproducer comprising a goose-neck flanged at one end, a washer and a disc peripherally secured to said flange and a diaphragm, said disc having a central dished portion and radially arranged 70 apertures therearound, and said washer having apertures adapted to register with said apertures in the disc.

In testimony whereof I have hereunto 75 subscribed my name in the presence of two subscribing witnesses.

FRANKLIN G. MATHIEU.
